ELECTRON DISCHARGE APPARATUS

John Edgar Keyston, Hayes, Frederick Hermes Nicoll, Ickenham, and Otto Klemperer, Hayes, England, assignors to Electric & Musical Industries Limited, Hayes, Middlesex, England, a British company

Application March 31, 1936, Serial No. 71,970
In Great Britain March 19, 1935

4 Claims. (Cl. 178—7.2)

The present invention relates to electron discharge apparatus in which a stream of electrons acted on by focusing means, is caused to sweep over a screen.

5 In known types of electron discharge device commonly referred to as cathode ray tubes, electrons are emitted from a cathode and accelerated towards and focussed upon a screen associated with the tube, by means of what is known as an electron lens. An electron lens may be of the electrostatic or electromagnetic type. In such tubes means may be provided for deflecting the beam out of a straight path to any desired degree, so that it falls on any desired spot of the 10 surface of the tube or screen. The deflecting means may comprise two pairs of parallel plates between which the beam passes, the plates of one pair being at right angles to the plates of the other pair. By applying suitable potential differences 15 between the plates, the beam is deflected out of a straight path due to the electrostatic field between the plates. Alternatively, the deflecting system may consist of a set of electromagnetic coils, usually placed outside the tube, deflection 20 being effected by passing a suitable current through the coils.

The electron lens system of the tube focuses the beam of electrons to a small spot which is at a fixed distance from the cathode.

25 30 The deflecting plates or coils sweep the focal point of the beam over part of the surface of a sphere, the centre of which may be considered to lie at the centre of the deflecting system. Therefore, in order that the beam may always be focused on the surface of the tube or screen, the latter must also be in the form of part of a sphere with its centre at the centre of the deflecting system of the tube.

This is often not a convenient arrangement.

40 45 For example, in certain cathode ray tubes, in particular those used for television transmitting purposes there is often employed a plane screen, the normal to which is set at an angle to the undeflected direction of the electron beam, which angle may be as great as 45°. When an electron beam is caused to scan such a screen, it is clear from what has been said above that the cross sectional area of the beam where it strikes the screen will vary as it moves over the screen, and consequently the size of the scanning spot on the screen will vary.

Fig. 1 shows a cathode ray tube of one conventional type without the present invention.

50 55 Fig. 2 shows schematically the operative ele-

ments of another conventional type of cathode ray tube without the present invention.

This may be more clearly understood by reference to Fig. 1 of the accompanying drawings in which there is shown diagrammatically part of a cathode ray tube of the kind referred to above. In the bulbous part 2 of the tube there is arranged a screen 1, which is scanned by a beam of electrons 3 from a cathode ray gun (not shown). In an undeflected position 3a the beam 10 is focused at a point 7 on the screen 1. Two electrodes 4 and 5 are provided for sweeping the beam of electrons over the screen in directions parallel to the plane of the figure. The beam of electrons 15 may be considered as being pivoted at the centre of the deflecting plates 4, 5 and the focused point of the beam 3 will describe an arc of a circle shown by the dotted line 6. In the positions 3b and 3c it is clear that the beam will not be in focus on the screen 1, but will fall on a considerable 20 area of the screen as shown at 8 and 9. Thus as the beam moves over the screen the area of the scanning spot will vary.

A similar disadvantage is present in cathode ray tubes in which a beam of electrons is focused 25 upon a fluorescent screen which is plane or has such curvature that the centre of curvature does not lie in the region of the deflecting system.

It is one object of the present invention to provide means whereby a beam of electrons remains 30 focused on a surface of the tube or screen placed therein during deflection of the beam, though said surface or screen is not shaped in the form of part of the surface of a sphere.

In cathode ray tubes in which the electron lens 35 is of the electrostatic type and the deflecting system comprises deflecting plates to which deflecting potentials are applied, it is found that the electrostatic field set up across the deflecting plates, more especially the field across the pair of plates nearest the electron lens, distorts the focusing field in the electron lens, with the result that the focal length of the electron lens varies, as the beam moves over the screen, in accordance with the magnitude of the deflecting potential.

45 It is a further object of the present invention to provide means whereby the focal length of the electron lens may be made substantially independent of the potential on the deflecting plates.

In Fig. 2 of the accompanying drawings there 50 is illustrated another known form of electron discharge device in which electrons, acted on by focusing means, are caused to sweep over a screen. Referring to Fig. 2, this known device comprises a transparent photo-electrically sensitive surface 55

10, on to which an optical image of the object to be transmitted is thrown by means of a lens 11. The photo-electrons emitted from the surface are focused upon an apertured diaphragm 12 to form 5 an electron image thereon. The electron image is caused to sweep over the aperture 13 in the diaphragm 12 so that the aperture 13 scans the electron image. Only those photo-electrons passing through the aperture 13 at any time are operative 10 in developing picture signals for transmission.

A coil 14 producing a steady and substantially uniform magnetic field in the general direction of electron travel is usually employed for focusing purposes. The electrons may be accelerated towards the diaphragm by maintaining the diaphragm 12 at a suitable positive potential with respect to the photoelectric surface of cathode 10. The aperture 13 is usually formed in the centre of the diaphragm 12 and the cathode 10 and the 15 diaphragm 12 are usually in the form of flat plates arranged parallel and facing one another and the magnetic focusing field due to the coil 14 is then arranged to be normal to the planes of these two plates. A thin cylinder of metal 15 20 (usually a coating upon the walls of the tube in which the electrodes are mounted) may be provided extending between regions close to the edges of the two plates 10 and 12 and thus surrounding the space through which the electrons 25 travel. This metal cylinder 15 is of high resistance and can be arranged to ensure that there is a uniform potential gradient along the space between the surface 10 and the diaphragm 12.

The electrons forming the image on the diaphragm 12 move in spiral paths, the motion being revoluble into a circular motion around a line of force and a straight line motion in the direction of the electrostatic field between the plates. The 30 time of flight of electrons between the plates 10 and 12 is dependent upon the distance and the potential difference between the plates and is independent of the path followed by individual electrons. The time required by an electron to 35 perform one revolution under the influence of the magnetic field is inversely proportional to the line integral of the magnetic field strength along the path between the plates. In the undeflected condition of the electron image this line integral has the same value for all electrons and it can 40 therefore be arranged by suitable choice of magnetic field strength and accelerating potential difference that in the undeflected condition all electrons have rotated through the same angle (for example they may have made one revolution) in the time taken to reach the diaphragm 45 12. Under these conditions a focused electron image will be formed on the diaphragm 12.

When however, the electron image is deflected (for scanning purposes) by suitable means which 50 may be electrostatic or electromagnetic (for example two pairs of electromagnetic deflecting coils, one pair of which are shown in section at 16 and 17, and one member of the other pair of which is shown in dotted lines in side view at 55 18), the line integral changes in value and hence the angle of revolution of electrons during their passage between the plates 10 and 12 changes. Since the time of flight has not changed the image is no longer sharply focused.

60 It is a further object of the present invention to provide means whereby this change of focus as the result of deflection in devices of this kind can be reduced or eliminated.

According to one feature of the present invention there is provided electron discharge appara-

tus comprising a cathode, an electron lens system for focusing electrons emitted from said cathode on to a screen and means for deflecting said electrons over said screen, wherein there are provided means for automatically varying the effective focal length of said lens system in accordance with the deflection of said electrons whereby changes in focus of the operative electrons from said cathode which would otherwise occur as said electrons are deflected over said screen are removed 10 or substantially reduced.

In a modification of the apparatus according to the preceding paragraph, where the electron lens system and the deflecting means operate electrostatically, the means for automatically varying 15 the effective focal length of said lens system in accordance with the deflection of said electrons may be such that changes of the focal length of said lens system which would otherwise occur as a result of the distortion of the electrostatic field 20 in said electron lens by said electrostatic deflecting means are removed or substantially reduced.

According to a further feature of the present invention there is provided electron discharge apparatus comprising a cathode, an electron lens 25 system for focusing electrons emitted from said cathode on to the surface of a screen, and means for deflecting the electrons emitted from said cathode over said screen surface, the screen surface not being a spherical surface having its 30 centre in the region of the deflecting means, wherein means are provided for automatically varying the effective focal length of said lens system in accordance with the deflection of said electrons in such a manner as to reduce changes 35 in sharpness of focus of the beam with deflection thereof.

According to the present invention in another aspect there is provided cathode ray tube apparatus comprising a cathode, an electron lens 40 system for focusing electrons from said cathode into a narrow beam upon the surface of a screen associated with the tube and means for deflecting the beam over the screen, the screen surface not being a spherical surface having its centre in the 45 region of the deflecting means, wherein means are provided for automatically varying the effective focal length of said lens system in accordance with the deflection of the ray in such a manner as to reduce changes in sharpness of focus of 50 the beam with deflection thereof.

According to the present invention in a further aspect there is provided apparatus for transmitting images of an object to a distance comprising a photo-electrically active screen, means for projecting upon said screen an optical image of an object to be transmitted, an apertured diaphragm spaced apart from said photo-electrically active screen, an electron lens system for focusing upon said diaphragm electrons emitted from said screen under the influence of light, to form an electron image thereon, and means for sweeping said electron image over said aperture in such a manner that said aperture scans said electron image, wherein there are provided means for varying the effective focal length of said lens system in accordance with the deflection of said image in such a manner that changes in the sharpness of focus of said electron image with 60 deflection thereof are reduced.

Further features of the invention will appear from the following description and appended claims.

The invention will now be described with refer-

ence to Figs. 3 to 10 of the accompanying dia-
grammatic drawings in which

Fig. 3 shows a cathode ray tube embodying one
feature of the present invention.

5 Fig. 4 shows a cathode ray tube having elec-
trostatic deflecting plates and embodying a fur-
ther feature of the present invention.

Fig. 5 shows a modification of part of the tube
of Fig. 4.

10 Fig. 6 shows a cathode ray tube having electro-
magnetic deflecting means and embodying a fea-
ture of the present invention.

Figs. 7 and 9 are explanatory diagrams.

15 Fig. 8 is a circuit diagram for use in carrying
out one feature of the present invention, and

Fig. 10 is a circuit associated with a known
form of cathode ray tube for use in carrying out
the present invention.

Referring to Fig. 3, the envelope of a cathode
20 ray tube consists of a neck portion 23 joined to
a bulbous portion 2. In the neck portion 23 are
arranged a heater coil 19, a cathode 20, a cathode
shield 21 which may in certain cases be used as a
modulator and an electron lens system comprising
25 a first anode 22 and a second anode 24.

These electrodes may be in the form of cylindri-
cal tubes of equal diameters. The first anode 22
is provided with two apertured diaphragms 22a
and 22b the diaphragm 22a being positioned at
30 the cathode end of the cylinder and the dia-
phragm 22b being positioned about two thirds of
the way along the cylinder from the cathode end.
The second anode 24 consists of a metal cylinder
without any apertured diaphragms.

35 The form of electrode assembly in the neck
portion 23 used in this embodiment of the inven-
tion is not of great importance and the arrange-
ment shown is by way of example only.

In the bulbous portion 2 of the tube is arranged
40 a screen 1 which is to be scanned by a beam of
electrons 3. The screen 1 may consist for ex-
ample of a mosaic screen comprising a number of
photo-electrically active metallic elements dis-
posed upon a mica sheet which is backed by a

45 metal signal plate. In using such a tube, an opti-
cal image of an object to be transmitted is pro-
jected upon the screen, and the screen is scanned
by means of the cathode ray beam 3 which is de-
flected over the screen 1 by means of two pairs
50 of deflecting plates, one pair of which is shown
at 4, 5. A second pair of deflecting plates (not
shown) at right angles to those shown at 4, 5
may be provided between the latter and the screen
1. Picture signals for transmission are taken
55 from the signal plate by a lead not shown. The
manner of operation of television transmission
apparatus of this kind is well known and need
not be further described.

In the following description it will be assumed
60 for the sake of convenience, that the view of
Fig. 3 is a side view of the tube, and that the
deflecting plates 4, 5, serve to deflect the beam 3
vertically up and down the screen 1.

In order to focus the beam on the screen in
65 every deflected position, the present invention,
in this embodiment, provides an electrode system
for varying the effective focal length of the elec-
tron lens system existing between the anodes 22
and 24 by the production, in the path of the ray,
70 of an asymmetrical electrostatic field. To this
end a silver coating 27 is formed on the walls
of the tube, extending partly into the neck por-
tion 23 and partly into the bulbous portion 2. The
silvering 27 extends to a plane normal to the
75 tube axis and located about half way between

the junction of the neck portion 23 with the
bulbous portion 2 and the lower edge of the
screen 1. This metallic coating may be main-
tained at a potential of say 500 volts positive
relative to the cathode 20, and may, if desired, be
5 connected to the second anode 24 of the main
electron lens system 22, 24.

A further ring-shaped metallized zone 28 of
relatively small area is provided upon the bul-
bous portion 2, the median plane of this zone 10
being inclined to the normal to the axis of the
tube so that portions thereof lie approximately
opposite the upper and lower edges of the screen
1. The ring-shaped zone 28 may be maintained
at a positive potential of say 1000 volts relative
15 to the cathode 20. The lower part of the zone is
much closer than the upper part thereof to the
edge of the 500 volt coating 27. The electrostatic
field between the two coatings is thus asymmetri-
cal and can be arranged to lengthen the effective
20 focal length of the electron lens system of the tube
when the ray is on the upper part of the screen
that is in position b relatively to the effective
focal length when the ray is on the lower part
of the screen in position c.

25 Clearly the field in which the correction is ap-
plied need not be an accelerating field. The ring-
shaped zone 28 may be maintained at a lower
potential than the metallic coating 27 so that
the correction is applied in a decelerating field.

30 In another arrangement according to the in-
vention a suitable varying potential which may be
derived from the deflecting circuit is applied to
an electron lens of the tube in such a way as to
alter the effective focal length of this lens in ac-
35 cordance with the deflecting current or voltage
applied to the deflecting means.

Such an arrangement is illustrated in Fig. 4
of the accompanying drawings.

Referring to Fig. 4, which represents a side
view of a cathode ray tube, in the tube are ar-
ranged a cathode 20 heated by a heater coil 19,
a cathode shield or modulator 21, first and second
anodes 22 and 24, deflecting plates 4, 5 and a
40 screen 1. These electrodes may have the form
described with reference to Fig. 3.

45 A second pair of deflecting plates indicated at
29 are provided between the plates 4, 5 and the
screen 1. Surrounding the space between the
first and second anodes 22 and 24 is arranged a
50 cylindrical electrode 30. This electrode will be
referred to as a "compensating electrode".

55 The first and second anodes 22 and 24 are
given suitable positive potentials relative to the
cathode 20, and the potential on the second anode
24 is made such in relation to the potential on
the first anode 22 that with zero potential on
the compensating electrode 30, the beam in the
undeflected condition is focused upon the screen.

60 The second anode 24 is connected to the de-
flecting plate 5 and to earth. An oscillator in-
dicated at 31 generates saw-tooth oscillations
which are taken from a terminal 32 and applied
to the plate 4 by lead 33 for the purpose of giv-
ing to the beam 3 the vertical component of a
65 scanning motion. Saw-tooth potentials of a
higher frequency applied to the plates 29 give the
beam the horizontal or line component of scan-
ning. The terminal 34 of the oscillator is con-
nected to earth.

70 Across the terminals of the oscillator 31 is con-
nected a resistance 37, and the compensating
electrode 30 is connected through a condenser 36
to a variable tapping point on the resistance 37.
In this way a voltage, derived from the deflecting

potential, of wave form similar to the latter and of the same sign, though of smaller amplitude, is applied to the compensating electrode 30.

Now when the plate 4 is at its maximum positive potential, the beam 3 falls on the top of the screen, and for the beam to be in focus, it is necessary for the focal length of the lens to be a maximum. This is brought about by the positive potential applied at this time to the compensating electrode 30. Similarly when the plate 4 is negative with respect to the plate 5, the focal length may be at a minimum; the negative potential then applied to the compensating electrode reduces the focal length of the electron lens between the two anodes 22 and 24. The amplitude of the derived potential applied to the compensating electrode 30 is adjusted to give correct compensation by adjusting the position of the tapping on the resistance 37.

20 The invention in this embodiment is not limited to the particular means described for applying to the compensating electrode 30 a potential derived from that on the deflecting plate 4. Any other suitable means may be provided for obtaining the derived potential.

30 The compensating electrode 30 may be given any suitable bias potential. As shown in Fig. 4, the electrode 30 is connected to the cathode 20 through a leak resistance 38, and thus the mean potential of the electrode 30 is the potential of the cathode 20. The electrode 30 may however, be given any desired bias for example by means of a battery inserted in series with the leak resistance 38. The potential of the electrode 30 is preferably given a bias potential not far removed from the cathode potential in order to ensure that substantially no current is collected thereby from the electron stream.

40 An alternative arrangement of first and second anodes and compensating electrode is shown in Fig. 5. In that figure the electron lens comprises a first anode in the form of a cylinder 22 having its end remote from the cathode disposed near to but usually not quite extending to the plane of the nearer end of a larger cylinder constituting the second anode. This latter cylinder has the form of a metallic coating 24 on the tube walls and may extend to a region close to the screen which may be arranged as shown in Fig. 4. A third cylinder 30 to act as the compensating electrode and having a diameter intermediate between the diameters of the first and second anodes 22 and 24 is arranged around the first anode 22 so as to overlap the latter and to project within the second anode 24. In one example, the first anode 22 is $\frac{1}{2}$ inch in diameter, the compensating electrode 30, $\frac{3}{4}$ inch in diameter and the second anode 24, 1 inch in diameter, and the compensating electrode 30 extends 8 millimetres beyond the end of the first anode 22.

50 The arrangement of Fig. 5 may be used in the same manner as described with reference to Fig. 4.

60 The invention may in this embodiment also be applied to tubes in which the beam is deflected over the screen by means of electromagnetic deflecting coils instead of by deflecting plates.

70 In Fig. 6 is illustrated a plan view of the tube shown in Fig. 4, with the deflecting plates 4, 5 and 29 omitted. Deflection is carried out by means of two pairs of deflecting coils, one pair of which is shown at 40 and 41 and the other pair of which is indicated at 42. The pair of coils 40, 41 which serve to deflect the ray vertically up and down the screen, that is in the

direction normal to the plane of the figure, are connected in series, and deflecting currents are passed through them from an oscillator indicated at 43. Across the terminals 44 and 45 of the oscillator 43 is connected a resistance 46. The compensating electrode 30 is connected to a tapping point on this resistance 46 through a condenser 47. A leak resistance 48 is connected between the compensating electrode 30 and the cathode 20. Thus a potential varying in accordance with the currents in the coils 40 and 41 is applied to the compensating electrode 30. The grid leak 48 serves to keep the compensating electrode 30 biased at cathode potential.

80 The electrode arrangement described with reference to Fig. 5 may also be applied to the case in which electromagnetic deflecting coils are used.

90 Where the change of focus of the beam with deflection is due to the use of an inclined plane screen, as described in the preceding examples, the compensation required is a linear function of the deflecting current or potential. If the change of focus is due to the use of forms of screens which are other than spherical (when no correction is required) or planar and inclined to the mean path of the beam, the compensation required may be nonlinear. The desired form of compensation can be obtained by suitable selection of the shape and position of the compensating electrode, and of the bias potential applied to it. The cross section of the compensating electrode 30 in planes normal to its axis is usually circular, but the cross section in planes containing its axis may be chosen to suit any particular case.

100 In the arrangement shown in Fig. 5, the compensating electrode may have the form of an apertured diaphragm the diameter of the aperture being intermediate the diameters of the first and second anodes 22 and 24.

110 It is usually desirable to arrange that the focus compensating means shall not alter the current in the electron beam and where this is the case the compensation should be effected between the last aperture which defines the beam and the screen because a change in the divergence of the beam will affect the number of electrons passing through an aperture arranged in the path of the beam of changing divergence.

120 It is however not necessary that the compensating electrode should be combined with the final electron lens as it may be arranged to co-operate with another electron lens nearer the cathode. For example, a part of the modulating cylinder usually provided, for example in cathode ray tubes used for television reception, for controlling the ray intensity may be insulated from the remainder and used for focal length control.

130 The various structures above described may be used to compensate for a change in focus irrespective of the cause of the change.

140 For example where the focus changes with change in beam current, a voltage or current dependent upon the modulating potential which produces the change in beam current may be applied to the compensating means above described so as to correct for the change in focus.

150 In certain cases it may be desirable to correct for the variation in distance from the centre of the deflecting system to points on a horizontal line across the screen. If the beam is deflected across the screen by means of a saw tooth potential or current it will move relatively slowly in one direction and rapidly back again. When the beam is at the beginning and end of its stroke the

focal length of the lens system must be greater than when the beam is half way across the screen. The correction need only be applied during the slower movement of the beam across the screen, since this is the only time when the beam has any useful function in this kind of apparatus. During the quick return stroke the accuracy of focus of the beam is immaterial. Referring now to Fig. 7 at (a) is shown the wave form of a scanning potential which is used to deflect the beam in horizontal lines across the screen. Potential is plotted as abscissa against time as ordinate. As the potential follows the lines PQ and RS the beam is moved comparatively slowly across the screen, and over the lines QR and ST the beam is made to return quickly to the other side of the screen. Now as explained above, the focal length of the electron lens must be greatest at the points P, Q, R and S, and shortest midway between PQ and RS, that is at points V and W. Thus the compensating potential must have a symmetrical zig-zag wave form as shown at (b) where at the points J, L and N the compensating potential is such that the electron lens has a maximum focal length and at the points K and M a minimum focal length, the latter corresponding to the central position of the beam on the screen.

A circuit suitable for deriving a wave form of the kind shown at (b) from a saw tooth potential as at (a) is illustrated in Fig. 8.

Referring to that figure, saw tooth potentials of the kind shown at (a) in Fig. 7 are applied to the terminals 51 and 52. The terminal 51 is connected to the control grid of a thermionic valve 53, the cathode of which is connected through a bias resistance 54 to the terminal 52. The anode of the valve 53 is connected through a resistance 55 to terminal 56 which is connected to the positive terminal of a source of potential (not shown). The terminal 52 is connected through lead 57 to the terminal 58 to which is connected the negative terminal of the source of potential.

Between the anode of valve 53 and the lead 57 is connected a condenser 59. Between the terminal 56 and the cathode of valve 53 is connected a variable resistance 60, by means of which the bias on the grid of valve 53 may be varied.

The operation of the circuit above described is as follows:—

The bias of the grid valve 53 is so adjusted that the valve passes no current when the potential of the applied wave form (a) of Fig. 7 falls below a value denoted by the line O O in that figure. While the valve 53 is nonconducting the condenser 59 is charged through the resistance 55, and it is arranged that the time constant given by the product $R_1 C_1$ where R_1 is the value of resistance 55 and C_1 the capacity of condenser 59 is large compared with the oscillation period of the saw tooth wave form applied across the terminals 51, 52. Condenser 59 will then change linearly. When the valve 53 begins to conduct, the potential of the condenser 59 will fall in sympathy with the potential on the grid of valve 53. Thus the potential of the condenser 59 will follow a wave form as shown at (b) in Fig. 7. This wave form is in antiphase to the potential applied to the grid of the valve 53. To reverse the phase of the potential on the condenser 59, there is provided a valve 63 which, with its associated circuits comprises an ordinary resistance-capacity coupled phase-reversing stage. The output terminal 66 of this phase reversing stage may be connected to the compensating electrode 30 of Fig. 4, 5 or 6.

In the above described arrangement, the re-

quired derived potential may be obtained by replacing the resistance capacity circuit 55, 59 by its equivalent resistance inductance circuit.

When correcting for changes in effective focal length of an electron lens arising from deflecting a beam of electrons over a screen the central region of which is nearer to the deflecting system than the edges, it may be necessary to apply a varying correcting potential which does not change linearly with time. Thus in certain cases it may be necessary to make the lines JK, KL etc. of the wave form of Fig. 7 (b) curved. This may be done by inserting a suitable correcting circuit between the terminal 66 of the circuit of Fig. 8 and the electrode to which the correcting potentials are applied.

Alternatively the potential applied to the compensating electrode 30 may be given a wave form which is other than linearly related to the deflecting potential. The alteration of wave form may be obtained by means of a suitable circuit; for example, a circuit whereby there may be derived from a saw tooth oscillation an oscillating potential which is substantially proportional to the integral of the saw tooth wave form. Such an oscillation may be obtained by feeding a saw tooth oscillation to a resistance and condenser in series. The integrated oscillations are taken from the terminals of the condenser. The time constant of the condenser and resistance is made long compared with the period of oscillation of the saw-tooth oscillation. The integrated wave form then consists of two parabolic arcs for each cycle of saw-tooth oscillation. The major arc corresponds to the slowly changing part of the saw-tooth wave form and this part of the integrated wave form may in suitable circumstances be fed to the compensating electrode 30.

Two connecting potentials may be applied to the compensating electrode 30, each derived from the corresponding deflecting potential, to correct for changes in focus of the beam in both directions.

As already mentioned in the introduction to this specification, variations in the focus of the beam occur in cathode ray tubes employing electrostatic electron focussing and electrostatic deflection due to the potential on the deflecting plates distorting the focussing field.

This difficulty may be overcome, according to the present invention, by methods similar to those described above for compensating for variation in the distance of different points on the screen. Thus a varying potential derived from the saw-tooth deflecting potentials may be fed to the compensating electrode 30, the amplitude of the potential being suitably chosen so that the effect of distortion of the deflecting potentials on the focussing field is eliminated.

An alternative arrangement by means of which elimination of distortion may be effected will be described with reference to Figs. 9 and 10.

Referring first to Fig. 10, a cathode ray tube is shown having a neck portion 23 and a frustoconical portion 20. At the base of the frustoconical portion 20 is a fluorescent screen 21. In the neck portion 23 is arranged an electrode system comprising a cathode 20 heated by a heating coil 19, a cathode shield 21, an accelerator electrode 22, a modulator electrode 23, a first anode 24 and second anode 25. The accelerator electrode is given a potential between that of the anode and cathode. The modulator may be biased at cathode potential, and modulating potentials in the negative direction applied to it

by a suitable circuit not shown serve to modulate the intensity of the beam. The modulating potentials may consist of received television signals. It will be assumed that the screen 71 is formed on part of a spherical surface the centre of which lies in the region of the deflecting system 4, 5, 29, in order that variations of focus of the beam due to configuration of the screen need not be considered in describing this embodiment 10 of the invention.

The second anode 24 and the deflecting plate 5 are connected together and maintained at, say, 2000 volts positive relative to the cathode 20. In order to cause the cathode ray beam to scan 15 the screen, saw tooth potentials, one at frame frequency and the other at line frequency, are applied to the deflecting plates. It is found as already mentioned, that, given constant voltages on the anodes 22 and 24, the cross sectional area 20 of the beam on the screen 71 where in the present case it forms a spot of light, varies according to the potential applied to the electrode 4. It is also found that for any potential on the plate 4, there is a corresponding potential of 25 the first anode 22 at which the spot size is a minimum. In Fig. 9 is a curve showing the relation between the potentials on the first anode 22 plotted as abscissae against potentials on the plate 4 plotted as ordinates for which the size of 30 the spot on the screen 71 is a minimum. It will be seen that the curve has an exponential form.

It will be clear that by applying to the first anode 22 of the tube of Fig. 10 a potential which 35 varies with the potential of the plate 4 according to the curve of Fig. 9, the beam may be focussed on the screen as a spot of substantially constant size. The circuit of Fig. 10 by means of which this varying voltage is applied will now be de- 40 scribed.

Two resistances 72 and 73 are connected in series. One end 74 of the combination is earthed and connected to the negative terminal of a source of potential (not shown). The other end 45 75 is connected to the positive terminal of the source of high potential. The first anode 22 of the tube is connected through lead 76 and one winding 80 of a transformer 77 to a tapping on resistance 72. The cathode 20 of the tube is connected through variable resistance 78 and lead 50 79 to a tapping on resistance 73. Thus the anode 22 is given a positive potential relative to the cathode 20. The potential on the accelerator electrode 67 may be derived in a similar way. 55 The cathode shield may also be connected to a tapping on resistance 73. In order not to complicate the drawings, however, the connections to the accelerator 67 and cathode shield 21 are omitted.

60 A screen-grid valve 81 has its anode connected through winding 82 of transformer 77 to terminal 83 which is connected to a source of positive potential (not shown) the negative terminal of which is earthed. The screening grid of the valve 81 is connected through a winding 84 of a transformer 85 to a terminal 86 which is connected to a suitable tapping on a source of potential. This may be the same source which is connected to the terminal 83. One end of a 65 winding 87 of transformer 85 is connected to the control grid of the valve 81 through a condenser 88, and the other end is connected to an earthed lead 89. The grid of the valve 81 is also connected to this lead through a variable resistance 70 90. The cathode of the valve 81 is connected 75

directly to the earthed lead 89. One end of a third winding 91 of the transformer 85 is connected to lead 87 and to terminal 92, and the other end to terminal 93.

Across the anode and cathode of the valve 81 5 is connected a condenser 94. The anode is also connected to the deflecting plate 4 of the cathode ray tube through a condenser 95 and a circuit comprising an inductance 96 shunted by a condenser 97 and resistance 98 in series. The plate 10 4 is connected to the plate 5 through a leak resistance 99 of high value. The anode of the valve 81 is also connected through a condenser 100 and resistance 101 to the lead 79.

The operation of the circuit is as follows. 15

The valve 81 and associated screening grid and control grid circuits form a normal blocking oscillator, the operation of which is well known and need not be fully described. It is sufficient to say that the valve becomes alternately conducting and non-conducting. The frequency of these changes is controlled by impulses applied across the terminals 92 and 93. These impulses may have the form of square topped pulses which are obtained from the synchronizing impulses of the received television signal. 20

While the valve 81 is non-conducting, the condenser 94 charges up through the impedance of the winding 82 of transformer 77. When the valve 81 conducts, the condenser 94 is rapidly discharged. The impedance of the winding 82 and the capacity of the condenser 94 are preferably made such that the curve showing the potential across the condenser 94 against time during the charging process has the exponential form of the 35 curve shown in Fig. 9. Thus the wave form of the oscillations generated in the anode circuit of the valve 81 have the form shown in Fig. 7 (a), modified in that the lines PQ and RS conform to an exponential curve. These oscillations are passed to the first anode 22 through winding 80 of transformer 77 and lead 76. The connections to the winding 80 are so arranged that the oscillations passed to the first anode 22 are in phase opposition to those passed to the 45 deflecting plate 4. The oscillations also pass through condenser 95 and the circuit 96, 97, 98 to the plate 4. The circuit 96, 97, 98 is a filter circuit so designed that the exponential saw-tooth wave form is converted into a straight line 50 saw-tooth wave form of the kind shown in Fig. 7 (a). Thus the beam of the tube is deflected in the usual fashion over the screen 71, and by applying the correcting voltage of exponential form to the first anode 22, variations in focus of the 55 spot on the screen are substantially removed.

Usually a change in voltage on the first anode 22 will result in a change in the current flowing to the second anode 24, and hence in a variation in brightness of the spot on the screen 71. 60 To avoid this, a part of the voltage applied to the first anode 22 is also applied, in phase opposition, to the cathode 20. This voltage is fed to the cathode 20 through the condenser 100 and resistance 101.

65 Preferably there is connected a decoupling condenser 102 between the tapping on resistance 72 and the earthed lead 89. In the operation of the above described arrangement, the voltage applied to the first anode 22 is of exponential 70 saw-tooth wave form. However, a considerable improvement in the constancy of spot size will be obtained if a linear saw-tooth wave form voltage is applied to the first anode. Thus the value of the condenser 94 may be made suf- 75

ficiently large to cause a linear saw-tooth wave form to be developed across it. In this case the filter circuit 96, 97, 98 may be omitted. If desired, in either of these arrangements the resistance 101 may be connected to the cathode shield 21, or in cases where a grid is placed between the cathode and first anode, the resistance 101 may be connected thereto. The time constant of the circuit comprising the condenser 100 and resistances 101 and 78 should be sufficiently large to prevent any phase distortion of the impulses passed through it.

If desired the circuit of Fig. 10 may be used with a cathode ray tube having a compensating electrode of the form described with reference to Figs. 4, 5 or 6, the lead 76 being connected thereto instead of to the first anode 22. In such a case, no variations in beam current occur and variation of the potential applied to the cathode then unnecessary. The circuit 100, 101 may therefore be omitted.

There will now be described methods of compensating for change of focus due to deflection of an electron image over a screen, as described and illustrated in the introduction to this specification with reference to Fig. 2. Referring again to Fig. 2 one way of doing this is to superimpose upon the magnetic focusing field due to the coil 14 an inhomogeneous steady magnetic field so that the composite magnetic field is stronger in the central than in peripheral regions. If the aperture 13 in the diagram 12 is centrally disposed, the centre of the image will be operative upon the aperture 13 in the undeflected condition and corners of the image will be operative on the aperture 13 with maximum deflection. Thus with no deflection the operative electrons travel in a relatively strong magnetic field and with maximum deflection the operative electrons travel from a region of relatively weak magnetic field into the stronger region. The latter electrons therefore travel in a path along which the line integral of the magnetic field strength is smaller than in the case of the former electrons. The time of revolution of the electrons which is inversely proportional to the line integral is therefore greater with deflection than without. By suitable arrangement the distribution of magnetic field strength may thus be made such that, in the case of all operative electrons, the time of flight is substantially equal to the time required for one revolution and the focus is thus maintained during the scanning process.

The inhomogeneous magnetic field may be produced by placing a permanent magnet on the axis of the coil 14 and some distance away from it. The magnet is arranged with its magnetic axis on the axis of the coil 14 and so placed that its field enhances that due to the coil 14. Alternatively the permanent magnet may be replaced by a further coil energized by a suitable current. This coil may take the form of a relatively short coil arranged coaxial with the main focusing coil at some distance away from it.

Another way in which the change of focus can be corrected is by making the accelerating electrostatic field between the two plates stronger in peripheral than in central regions. In this way the time of flight is made shorter for electrons which are operative in the deflected condition than for electrons which are operative in the undeflected condition. The required electrostatic field distribution may be obtained by arranging that the surface of the cathode 10 facing the diaphragm 12 or the surface of the

diaphragm 12 facing the cathode 10, or both these surfaces, are concave.

In both the examples given above, the desired effect is obtained by providing a suitably inhomogeneous magnetic or electric field. A similar result can also be obtained by producing variations in the field so that the field strength varies in accordance with the part of the image which is active upon the scanning aperture 13. In such cases the field may be homogeneous. The desired variations in the field may be obtained (in the case where the field to be varied is the electrostatic field) by superimposing upon the normal steady potential difference between the cathode 10 and the diaphragm 12 a compensating potential difference varying in a suitable manner in accordance with the deflection. For example where the deflection is effected in known manner with the aid of two electrical oscillations of saw-tooth wave form, one at line scanning frequency and the other at picture frequency, the varying potential differences required for focus compensations may be derived from these two saw-tooth oscillations. These derived corrective potential differences will normally be arranged to be constituted by components of twice line frequency and twice picture frequency, and may have the wave form indicated in Fig. 7 (b). They may be derived from the saw-tooth scanning currents by means of circuits of the form illustrated in Fig. 8. Clearly, if correction is to be applied in both scanning components, one such circuit will be needed to derive compensating potentials from the scanning oscillations at line frequency, and another to derive compensating potentials from the scanning oscillations at frame frequency. The two compensating potentials are then combined and applied to the cathode 10 or diaphragm 12 in suitable phase relationship to the scanning oscillations.

We claim:

1. Electron discharge apparatus comprising a cathode, a screen, an electrostatic electron lens system for focussing electrons emitted from said cathode on to said screen, said electron lens system comprising two cylindrical lens electrodes juxtaposed co-axially and being associated with means for maintaining a potential difference between said lens electrodes, means for deflecting said electrons over said screen, a compensating electrode positioned in the neighbourhood of the region of juxtaposition of said lens electrodes, said compensating electrode being associated with compensating means for varying the potential thereon relatively to that of said lens electrodes according to one or both of the two varying oscillations which, in operation, produce the deflection of the electrons, thereby changes in focus of the operative electrons from said cathode which would otherwise occur as said electrons are deflected over said screen are removed or substantially reduced.

2. Electron discharge apparatus as claimed in claim 1, wherein means are provided for generating and applying, to effect deflection of the electrons, a deflecting saw-tooth wave form, and wherein said compensating means for varying the potential on said compensating electrode comprise a circuit for developing from the saw-tooth oscillation and feeding to the said compensating means a potential of substantially symmetrical zig-zag wave form having a frequency equal to that of the saw-tooth oscillations.

3. Electron discharge apparatus as claimed in claim 1 wherein said lens electrodes are equal in diameter and said compensating electrode is annular and surrounds the space between said lens electrodes.
4. Electron discharge apparatus as claimed in claim 1 wherein said lens electrodes are of dif-

ferent diameters, and the compensating electrode overlaps one of said lens electrodes and projects within the other of said lens electrodes.
